US00D926018S

(12) **United States Design Patent** (10) Patent No.: **US D926,018 S**
(45) Date of Patent: **** Jul. 27, 2021**

(54) **KNOB**

(71) Applicant: **Dormakaba USA INC.**, Indianapolis, IN (US)

(72) Inventors: **John Andrew Snodgrass**, Indianapolis, IN (US); **Michael Hans Viklund**, Indianapolis, IN (US); **Brendon Allen**, Indianapolis, IN (US)

(73) Assignee: **dormakaba USA Inc.**, Indianapolis, IN (US)

(**) Term: **15 Years**

(21) Appl. No.: **29/739,938**

(22) Filed: **Jun. 30, 2020**

Related U.S. Application Data

(62) Division of application No. 29/686,585, filed on Apr. 5, 2019, now Pat. No. Des. 891,901.

(51) **LOC (13) CI.** **08-06**

(52) **U.S. Cl.** **USPC D8/311**
